UNITED STATES PATENT OFFICE.

HARRY BROUSSEAU, OF NEW YORK, N. Y.

ROTARY PUMP, &c.

1,128,579.

Specification of Letters Patent. Patented Feb. 16, 1915.

Application filed August 14, 1912. Serial No. 715,053.

To all whom it may concern:

Be it known that I, HARRY BROUSSEAU, a citizen of the United States, and a resident of New York, borough of Brooklyn, county of Kings, and State of New York, have invented certain new and useful Improvements in Rotary Pumps, &c., of which the following is a full, clear, and exact description.

This invention relates more particularly to rotary pumps having a plurality of cylinders in each of which a piston is adapted to move.

One of the important objects of the invention is to provide a plurality of cylinders mounted to rotate with a shaft, and a second rotary shaft to which the pistons of the cylinders are connected and which is eccentrically arranged with respect to the first-mentioned shaft so that during the rotation of the shafts a relative movement is imparted between the pistons and cylinders to cause a relative reciprocatory movement, and in such a way that the rods connected to the pistons may be mounted upon independent pins and in vertical alinement thus simplifying the construction of such pumps as ordinarily constructed and overcoming the necessity of connecting all the pistons to a single stationary crank pin.

Other objects of the invention are to provide a plurality of cylinders having a common head and having openings in said head of a smaller size than the cylinders to cause the water in passing through the openings to offer sufficient resistance to force the cylinders and shaft which carries the cylinders toward the discharge side of the casing in order to prevent leakage and to avoid the necessity of having a packing at this point; and to provide a simple and efficient pump in which a pump runner is provided with curved wings or vanes and which is adapted to counteract the centrifugal force due to the rotary motion of the cylinders which tends to force the water outward, the said runner serving to draw the water through the inlet and to deliver the same to the cylinders.

A further object of the invention is to provide a connection between one side of the casing and the suction side thereof so

that any leakage occurring in the casing on one side thereof may be withdrawn to the other side.

A still further object of the invention is to provide a pump in which the rotary parts of the invention are substantially balanced so as to have an easy and uniform movement.

A still further object of the invention is to provide a pump in which practically no packing and valves are required between the several wearing parts, and which parts may be operated by belt, motor, or other driving means.

With these and other objects in view, the invention will be hereinafter more particularly described with reference to the accompanying drawings, which form a part of this specification, and will then be pointed out in the claims at the end of the description.

In the drawings, Figure 1 is a longitudinal section, partly in elevation, of one form of pump embodying my invention. Fig. 2 is an elevation, partly in section, of the pump follower or runner and the cylinder casing. Fig. 3 is a detail view of the annular cylinder head. Fig. 4 is a vertical section, taken on the line IV—IV of Fig. 1; and Fig. 5 is a detail elevation of the pump runner.

While I show and describe the invention as applied to rotary pumps, it will be understood that some of the parts may be used and the invention so modified as to adapt the same for rotary engines, air compressors, and the like, and that while the rods connecting the pistons to one of the shafts are shown as each arranged upon an independent pin, it will be understood that where two or three cylinders are used, for example, the rods may be held directly on the end of the shaft without departing from the character of the invention.

The casing 10 has a base 11 to which a boss 12 is connected by an upright 13. The boss 12 has a bushing 14 which forms a bearing for a shaft 15, which latter shaft may have a pulley to be driven by a belt, or said shaft may be operated by an electric motor or in any other desired way. A pin disk

16 is held to the shaft 15 and projecting from said disk is an arm 17 which is connected by a link 18 to the cylinder casing 19, the latter forming a part of a pump runner or member 20 and rotating with said runner. The pump runner may be formed integral with a shaft 21 and said shaft is rotatably mounted in a bushing 22 which is held in a boss 23 of the casing head 24. The 10 casing head 24 like the pump casing 10 is cylindrical in form and is provided with a flange 25 which may be rigidly secured to a flange 26 of the pump casing, and on the inner surface thereof may be inclined or 15 conical, as at 27. The runner 20 and its shaft 21 is held against lengthwise movement in the bushing 22 by a collar 29 secured on the outer end of the shaft 21, the said collar being inclosed within a cap 30 which 20 has a threaded portion adapted to engage a threaded end of the casing head boss 23.

A plurality of pistons 31 are adapted to work in a corresponding number of cylinders 32. These cylinders 32 form a part of 25 the cylinder casing 19 and are radially arranged about the runner 20. A ring 33 is arranged around the outer ends of the cylinders and forms a head for said cylinders. The cylinder casing 19 with the cylinders 30 form substantially an annular body and has the central portion cut-away to adapt the pin disk 16 to project within the same, and arranged on the pin disk are a plurality of pins 34 arranged circumferentially about 35 the shaft 15, said pins having their outer ends held in a disk 35. There are six cylinders shown though this number may vary, and each cylinder has its piston 31. Each piston 31 is hollow and has a pin 36 to 40 which one end of the connecting rod or link 37 is held, the other end of said rod being connected to its corresponding pin 34. The shafts 15 and 21 are eccentrically arranged with respect to each other and are off-center 45 or eccentric to the extent of substantially one-half of the stroke of the pistons. It will be evident that by reason of the link 18 connecting the shaft 15 to cylinder casing 19 that the two shafts 15 and 21 will 50 rotate in unison, and that by reason of the eccentric arrangement of said shafts, the pistons will be reciprocated within the cylinders during such rotary movement.

The casing 10 is provided with an intake 55 or inlet 38 and a discharge 39. The intake end of the casing is connected to substantially one-half of the cylinders at the lower part of the casing so as to take in simultaneously three of the cylinders, and the discharge 60 connects by an enlarged and tubular part 40 with three of the discharging cylinders. As the pistons are reciprocated, as already explained, the water or other liquid or material will pass from the intake to the three 65 lower cylinders and drawn therein during

the rotary movement of the shafts 15 and 21, at which time the pistons of the three upper cylinders will be moved to discharge the material or liquid from said upper cylinders into the enlarged part 40 and to and through the discharge 39. The rotary movement of the cylinders will have a tendency to throw the water outward owing to their speed and to centrifugal force, and such action of the cylinders is counteracted by the pump runner or member 20. The pump runner 20 has a plurality of vanes or wings 41 which are so arranged that during the rotary movement of the runner the water will be drawn from the intake and delivered to the cylinders in such a way as to counteract the centrifugal force of the cylinders to force the water outward.

The cylinder head 33 has slots 42 substantially less in area than the area of the cylinders so that during the discharge of the cylinders the said slots will offer resistance to the discharge of the water, and such resistance will lift the head and cylinder casing toward and force the head against that end of the pump casing 10, thereby preventing leakage and compensating for any wear that might occur at the discharge side of the casing should any leakage occur between the cylinder head 33 and the outer periphery of the runner by reason of said head being forced against the surface of the outer stationary casing, such leakage would be back to the intake side and would not interfere with the proper operation of the pump. The construction just referred to is designed to reduce leakage in the discharge or pressure side of the pump.

If leakage should occur from the intake side of the casing to the side 43 of said casing, a pressure might be created therein sufficient to force the face 28 of the runner hard against the inclined or conical face 27 of the head 24 and be otherwise objectionable. To avoid this, a pipe 44 has one end connected to the part 43 of the casing on the opposite side of the cylinders and this pipe has its other end connected to the intake portion so that during the action of the pistons any water or other fluid or material that might pass to the side 43 of the casing is withdrawn therefrom and forced by the pistons into the discharge.

From the foregoing, it will be seen that a simple and efficient pump is provided in which the cylinders and the means for operating the pistons are eccentrically arranged with respect to each other to cause a relative movement during the rotary movement of the pistons and cylinders; that simple means is provided to prevent leakage; that simple and efficient means is provided whereby the centrifugal action of the cylinders is counteracted; that said pump is simple in construction and the parts so ar-

ranged that they will be substantially balanced in operation; and that the invention is such that parts thereof may be used in other connections than with pumps.

5 Having thus described my invention, I claim as new and desire to secure by Letters Patent:—

1. The combination of a casing having elongated inlet and discharge openings, a 10 rotary cylinder casing having a plurality of radially arranged cylinders, a runner having blades and counteracting the centrifugal effect of the cylinders, a shaft to which the runner is held, a piston for each cylinder, a second shaft eccentrically arranged with respect to the first-mentioned shaft, connections between the second shaft and the pistons, and means for operatively connecting the shafts to rotate in unison.

20 2. The combination of a rotary cylinder casing having a plurality of cylinders, a member rotating with the cylinders and having means to create suction and to deliver water to said cylinders to counteract the 25 centrifugal effect of the cylinders, a shaft to which the member is held, a piston for each cylinder, a shaft eccentrically arranged with respect to the first-mentioned shaft, and connections between the second shaft 30 and the pistons.

3. The combination of a casing having elongated inlet and discharge openings, a 35 rotary cylinder casing having a plurality of radially arranged cylinders, rotary means for counteracting the centrifugal effect of the cylinders, a shaft rotatable with the rotary means and the cylinders, a piston for each cylinder, a shaft eccentrically arranged with respect to the first-mentioned shaft, connections between the second shaft 40 and the pistons, and means for operating the shafts in unison.

4. The combination of a casing having inlet and discharge openings, a rotary cylinder casing having a plurality of radially arranged cylinders, a runner having means to deliver water to the cylinders to counteract the centrifugal effect of the cylinders, a shaft to which the runner is held, a piston for each cylinder, a second shaft eccentrically arranged with respect to the first-mentioned shaft, rods connecting the second shaft and the pistons, and means for rotating the shafts in unison.

55 5. The combination of a casing having inlet and discharge openings, a rotary cylinder, a piston held to reciprocate in the cylinder, and pumping means discharging into the cylinders for counteracting the centrifugal effect of the cylinder.

6. In a rotary pump, the combination of a plurality of cylinders, a piston for each cylinder, rotary shafts connected to the pistons and cylinders and eccentrically arranged with respect to each other, a casing

inclosing the cylinders and having inlet and discharge openings and having chambers on opposite sides of the cylinders, a connection from one side of the casing to the other to withdraw any leakage from one side of the 70 casing to the other, and centrifugal pumping means for delivering water to the cylinders during the rotation thereof.

7. In a rotary pump, the combination of a plurality of rotary cylinders, a piston for 75 each cylinder, shafts connected to the pistons and cylinders, a casing inclosing the cylinders and having inlet and discharge openings and having chambers on opposite sides of the cylinders, a connection from one 80 side of the casing to the other to withdraw any leakage from one side of the casing to the other, and a pump runner for delivering water to the cylinders and counteracting the centrifugal effect of the cylinders during 85 the rotation thereof.

8. In a rotary pump, the combination of a casing, a plurality of cylinders arranged within the casing, a plurality of pistons, shafts eccentrically arranged with respect to 90 each other and connected to the pistons and cylinders, means for rotating the shafts, cylinders and pistons in unison, and a cylinder head for the cylinders having elongated openings of less area than the cylinders to 95 cause the head to be forced to one side against the casing to prevent leakage.

9. The combination of a casing, a plurality of cylinders arranged within the casing, a plurality of pistons, shafts eccentrically 100 arranged with respect to each other and connected to the pistons and cylinders, means for rotating the shafts in unison, and an annular cylinder head for the cylinders having openings of less area than the cylinders 105 to cause the head to be forced to one side against the casing to prevent leakage.

10. The combination of a casing, a plurality of rotary cylinders arranged within the casing, an annular head for all the cylinders, a plurality of pistons one for each cylinder, shafts eccentrically arranged with respect to each other and connected to the pistons and cylinders and to rotate therewith, and means whereby the head and cylinders 115 may be forced to one side against the casing to prevent leakage.

11. The combination of a plurality of rotary cylinders, pistons relatively movable in said cylinders, a shaft operatively connected to the pistons, a pump runner, a shaft eccentrically arranged with respect to the first-mentioned shaft and connected to said runner to rotate therewith, and means for rotating the cylinders and runner in unison 125 and both acting to cause the water to flow into the cylinders.

12. The combination of rotary means including a plurality of cylinders, pistons movable in said cylinders, means whereby 130

the pistons may be moved relatively with respect to the cylinders, and an element having means to draw and force water and to deliver the same to the cylinders and to 5 counteract the centrifugal action of said cylinders.

This specification signed and witnessed this twelfth day of August A. D. 1912.

HARRY BROUSSEAU.
